UNITED STATES PATENT OFFICE

2,007,803

FILLING NIPPLE AND STOPPER THEREFOR

Patrick Kelly, New York, N. Y.

Application May 10, 1934, Serial No. 724,872

3 Claims. (Cl. 152—12)

This invention relates to filling nipples and plugs therefor for use in connection with inflatable articles.

One of the objects of the invention resides in 5 a filling nipple and plug for use in connection with inflatable arch supports, foot balls, toy balloons, and other like inflatable articles which facilitates the inflation and deflation of the same. The device is so constructed that when an 10 inflatable article is inflated, the fluid pressure acts upon the plug to prevent accidental displacement of the same relative to the filling nipple.

Another feature of the invention is to provide 15 a combined filling nipple and plug which is wholly constructed of rubber to eliminate the use of metallic and other hard materials which are objectionable for certain uses to which the invention may be applicable.

A further object of the invention is the provision 20 of a filling nipple and plug which is simple and inexpensive of construction, and positive in its action to prevent leakage when in use upon an inflatable article.

With these and other objects in view, the 25 invention resides in the certain novel constructions, combination and arrangement of parts, the essential features of which are hereinafter fully described, are set forth in the appended claims, and are illustrated in the accompanying drawing, 30 in which:

Figure 1 is a fragmentary side elevational view 35 of a shoe with parts broken away and illustrating the invention in use upon an inflatable arch support shown in position therein.

Figure 2 is a fragmentary horizontal section 40 through the shoe illustrating the arch support in top plan with a portion broken away.

Figure 3 is a vertical longitudinal sectional view 45 of the arch support per se taken on the line 3—3 of Figure 2.

Figure 4 is an enlarged detail fragmentary 50 sectional view on the line 4—4 of Figure 2.

Figure 5 is a view similar to Figure 4, but showing 55 the filling nipple in elevation and withdrawn from its guard.

Figure 6 is an enlarged detail vertical sectional view through the filling nipple.

Figure 7 is a horizontal sectional view on the 50 line 7—7 of Figure 6.

Figure 8 is a view similar to Figure 6 but showing 55 the ball plug member separated from the filling nipple.

Figure 9 is a detail vertical transverse sectional view of the line 9—9 of Figure 2.

Referring to the drawing by reference characters, the numeral 10 designates an elongated substantially flat inflatable air bag or cushion which includes a front body portion A and an integral offset heel extension portion B extending outwardly at an angle with respect to the longitudinal axis of the body portion A. The air bags will be constructed for right and left shoes, although in the drawing I have shown the same for use within a right shoe S. For use within 10 a left shoe, the heel extension B will extend in a direction opposite to that shown in Figure 2.

The air bag 10 is preferably constructed of 15 tubular rubber and the heel end is sealed by folding the upper wall beneath the lower wall 15 and vulcanizing or cementing the walls together as at 11. The front end of the air bag is also sealed in the same manner as the heel end as at 12, but the front end is folded beneath the bottom of the air bag as at 13 and the lapping 20 surfaces are vulcanized or cemented together as at 14 to provide a partition wall 15 which terminates short of the extreme front wall to provide a restricted passage 16 between the forward superposed compartments 17 and 18. By 25 providing the double compartment at the front of the air bag, I increase the capacity of the bag without materially increasing the thickness and provide a compartment or chamber 17 in which air may be trapped in a manner and for a 30 purpose to be presently explained.

The air bag 10 is divided transversely by two 35 spaced partitions 19 and 20 which divide the bag into the forward compartment 18, heel compartment 21 and an intermediate compartment

22. The partitions are formed by cementing or 40 vulcanizing the top and bottom walls of the bag together, a portion adjacent opposite sides of the bag being left unsecured to provide restricted 45 communicating passages or choke openings 23 and 24. The passage 23 is located adjacent the outer side of the air bag and connects the compartments 21 and 22, while the passage 24 establishes communication between the compartments 18 and 22 and is located adjacent the inner side of the air bag. The walls of the passage 24 are reinforced by a short rubber tube 25, but not the walls of the passage 23 which underlies the heel of the foot when in use. The partition 50 55 55

20 extends diagonally into the heel extension portion B to produce a compartment 21 of substantially triangular shape in plan so that pressure thereon by the heel of the foot during walking will cause a proportionate amount of air to

be trapped in corner portion where the partition 28 and inner side wall of the air bag meet. Although I have described in detail an inflatable arch support with which the inflatable nipple and plug now to be described can be used, I wish it to be understood that the novel nipple and plug may be used in connection with other inflatable articles such as foot balls, toy balloons and the like.

10 Cemented or vulcanized to the exterior of the inner side of the air bag intermediate its ends or between the plane of the partitions 19 and 20 is a reinforcing piece of rubber 25. The reinforcing piece and the under wall which it overlaps are provided with aligned openings 26, while secured to the reinforcing piece and surrounding the opening 26 therein, is one end of a rubber inflating nipple 27. The opposite end of the nipple 27 is closed and provided with a slit or air opening 28. The closed end of the nipple is folded within and beyond the open end as best seen in Figure 6 so that the slit or opening 28 communicates with the interior of the air bag through the opening 26. The inner wall of the nipple is provided with a longitudinal V-shaped rib 29 which serves to maintain a portion of the double walls 30 in spaced relation to maintain the air pockets 31 between the walls open to the pressure of air within the air bag. However, to prevent the reversing or accidental outward unfolding of the folded nipple, a portion of the double walls are cemented together as at 32. Seated wholly within the outer open folded end of the nipple is a rubber ball plug member 33, which is held in sealing engagement with the inner walls 30 by the air pressure within the pockets 31. The ball valve member may be squeezed from the nipple for inflation or deflation purposes, as seen by reference to Figure 8, but when the air bag is inflated the air pressure acting upon the inner walls 31 maintains an airtight joint between said walls and the ball plug member.

45 The air bag 10 is vulcanized or cemented on a base of stiff rubber or rubberized cotton fabric 34 of a size and shape to fit into the inside of a shoe, the ends of the base terminating short of the end seams 11 and 12.

50 The base 34 is provided with an opening 36 to facilitate the downward passage of the nipple 27 and secured to the underside of the base about the opening 36 is a block of rubber 37 of a thickness to enable the outwardly projecting end of the nipple to be sunk within an opening 38 therein as best seen in Figure 4. The rubber block guards the nipple against the pressure of the foot and prevents irritation to the foot.

55 By reference to Figure 3 of the drawing, it will be seen that when the air bag is inflated, three separate pillows or cushions are provided, graduating in height from the rear heel cushion or compartment 21 to the front cushion or compartment 18, the air in the compartments adapted to be partially displaced from one compartment to another during the natural walking movements of the user.

60 In the drawing, I have illustrated the invention in use upon a shoe S for receiving the right foot of a wearer, and it will be noted that when the device is positioned therein, the air bag extends from the outer portion of the heel, thence beneath the inner longitudinal arch and the forward end of the air bag extends at an angle 75 toward the outer side of the shoe. By this ar-

5 arrangement, the heel of the foot is supported and cushioned by the compartment 21, while the intermediate compartment 22 supports and cushions the inner longitudinal arch of the foot, the forward compartments 17 and 18 terminating short of the ball of the foot and acting to support and cushion the metatarsal arch. During a walking operation, pressure is first exerted upon the heel pocket or cushion 21, and a part of the air therein is gradually displaced and pushed forward into the pockets or compartments 22, 18 and 17. A portion of the air remains trapped in the corner of the compartment 21. As the arch and sole of the foot move downward and the pressure of the foot acts upon the compartments 22 and 18 successively, the air therein will be likewise displaced but not to the extent to fully exhaust the entire air from these compartments. A portion of the air is trapped in the under compartment 17 to assure an air cushion support for the metatarsal arch. By reason of the restricted passages between the compartments or pockets, it will be seen that a gradual displacement of the air from one compartment to the other takes place.

10 I have found from actual practice that it is not necessary to extend an arch support to the ball of the foot in order to obtain the desired support of the inner longitudinal arch and metatarsal arch of the human foot, and by terminating the air bags short of the ball of the foot, a more comfortable and efficient supporter is produced.

15 While I have shown and described what I deem to be the most desirable embodiments of my invention, I wish it to be understood that such changes as come within the scope of the appended claims may be resorted to if desired.

20 Having thus described the invention, what I claim as new and desire to secure by Letters Patent of the United States, is:—

25 1. An air check valve for use in the inflation of inflatable articles comprising a rubber nipple closed at one end and open at its other end, the closed end being reversed and folded inwardly to provide a double wall structure and extending through the open end, said closed end having a restricted passage therein, a portion of the double walls being secured together to prevent unfolding of said nipple, and a ball valve member seated within said nipple and insertible through the folded end thereof.

30 2. A device for use in the inflation and deflation of inflatable articles comprising a rubber tubular nipple closed at one end and open at its other end, the open end adapted to be connected with an inflatable article, the closed end being reversed and folded inwardly to provide a double wall structure and extending through the open end, said closed end having a normally closed slit therein, a portion of the double walls being secured together to prevent unfolding of the folded nipple, and a plug member of a size greater than the size of the normal cross sectional area of the passage formed by the inner walls of the double wall structure and insertible through the open folded end thereof to distend the walls thereof of said nipple to close the passage therethrough.

35 3. A device for use in the inflation and deflation of inflatable articles comprising a rubber nipple closed at one end and open at its other end, the open end being in communication with the interior of the article, the closed end being

reversed and folded inwardly to provide a double wall structure and extending through the open end, said closed end having a restricted passage therein, and a ball plug member insertible wholly within said nipple beyond the fold to distend the walls of the same whereby the space between

the walls at the fold may become inflated to cause the inner walls to engage the outer facing portion of the ball plug member to maintain the same in seated position.
